[57] CLAIM

The ornamental design for a holder for business card, as shown and described.

DESCRIPTION

FIG. 1 is a front perspective view of a holder for a business card showing my new design;

FIG. 2 is a rear elevational view thereof;

FIG. 3 is a top plan view thereof;

FIG. 4 is a bottom plan view thereof;

FIG. 5 is a left end elevational view thereof;

FIG. 6 is a right end elevational view thereof;

FIG. 7 is a front perspective view of a holder for a business card of a second embodiment of FIG. 1;

FIG. 8 is a rear elevational view thereof;

FIG. 9 is a top plan view thereof;

FIG. 10 is a bottom plan view thereof;

FIG. 11 is a left end elevational view thereof;

FIG. 12 is a right end elevational view thereof;

FIG. 13 is a front perspective view of a third embodiment of FIG. 1;

FIG. 14 is a rear elevational view thereof;

FIG. 15 is a top plan view thereof;

FIG. 16 is a bottom plan view thereof;

FIG. 17 is a left end elevational view thereof;

FIG. 18 is a right end elevational view thereof;

FIG. 19 is a front perspective view of a fourth embodiment of FIG. 1;

FIG. 20 is a rear elevational view thereof;

FIG. 21 is a top plan view thereof;

FIG. 22 is a bottom plan view thereof;

FIG. 23 is a left end elevational view thereof;

FIG. 24 is a right end elevational view thereof;

FIG. 25 is a front perspective view of a fifth embodiment of FIG. 1.

FIG. 26 is a rear elevational view thereof;

FIG. 27 is a top plan view thereof;

FIG. 28 is a bottom plan view thereof;

FIG. 29 is a left end elevational view thereof; and

FIG. 30 is a right end elevational view thereof.
